CLAIM

The ornamental design for a IC card reader/writer, as shown and described.

DESCRIPTION

FIG. 1 is a top, front, right side perspective view of a IC card reader/writer according to our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof, the right side elevational view being a mirror image; and,

FIG. 7 is a top, front, right side perspective view thereof, the cover shown in closed position.

1 Claim, 6 Drawing Sheets
